JULES ETIENNE HANSOTTE, OF COLOMBES, FRANCE.

BRAKE-CAR.

1,325,151.

Specification of Letters Patent. Patented Dec. 16, 1919.

Application filed April 27, 1918. Serial No. 231,161.

To all whom it may concern:

Be it known that I, JULES ETIENNE HANSOTTE, citizen of the Republic of France, and resident of Colombes, France, (post-office address, 12 Rue Besson,) have invented a new and useful Brake-Car, which improvements are fully set forth in the following specification.

It may be necessary to raise to heights, 10 which may be easily accomplished by means of steep inclines, railway material, artillery material, etc., which not being provided with brakes, or only with brakes of feeble power, is able to travel upon gentle inclines 15 only, owing to the friction between the wheels and the two rails of the track.

To reach such heights therefore it is necessary to construct indirect tracks of great length necessitating sometimes cuttings, and 20 passing through localities which it would be preferable to avoid and other engineering work of considerable magnitude.

The present invention relates to a brake car equipped with horizontal driving wheels 25 in addition to the usual vertical wheels, the horizontal wheels acting against an auxiliary central rail for the purpose of augmenting the frictional engagement and 30 brake power of the vehicle. The improved brake mechanism satisfies these desiderata, being interpolated between the trains to be 35 hauled as will be hereinafter explained. The vehicle to which the invention is to be applied may be a locomotive tender, flat car, box car, etc., and will hereinafter be merely 40 termed the "vehicle," and such vehicle, irrespective of its character, will have a very great frictional engagement with the central rail besides that natural to its own weight 45 acting upon the two rails of the track. The vehicle will also have very powerful brakes besides the ordinary ones, which act on the 50 vertical wheels, and it is so constructed as to allow the brakes to be applied with perfect reliability on steep inclines without requiring modification of the railway or artillery material, etc., even when it is not provided with brakes or when its brakes are weak or worn, in a word without altering the material, even that intended for level tracks or 55 gentle inclines.

The said vehicle is constructed to run on the usual tracks of normal or narrow gage, to which by the application of the present 55 invention, the central rail is simply added,

at those sections only which have steep inclines upon which the frictional engagement and brake power of the horizontal wheels are to be used.

For passing around the curves of the 60 track, particularly those of short radius, if the rolling stock is not provided with a central buffer it is necessary to provide the brake mechanism above mentioned with special lateral buffers against which the thrust, 65 which is increased on steep inclines, shall be equally distributed.

In practice on curves, for the rolling stock, the buffer placed in the interior thereof takes the major portion or even the 70 whole of the thrust; on the other hand if the distance of the buffers from the end axles is not the same for the brake mechanism as for the vehicle to which the brake mechanism is attached, the buffers of the brake 75 mechanism will be eccentric to those of the vehicle. The thrust by a single eccentric buffer would produce an abnormal strain on the stock as well as jamming (or hugging) of their wheels against the two rails of 80 the track. The said brake is not heavy although capable of considerable brake power, and the vehicle to which it is to be attached may be loaded with water, coal, artillery ammunition or various other goods 85 to be transported.

The brake mechanism can be applied to railways, tramways and tractors worked by steam, electricity, compressed air or other means. 90

In the following description there is described a vehicle with balanced buffers, but it must be understood that it is only an example of the application of the devices forming the subject matter of the present 95 invention.

Figures 1 to 8 inclusive of the accompanying drawing relate to a flat car with two axles, having three pairs of horizontal wheels for applying a braking action on the central rail, and at each end a system of balanced buffers mounted upon a beam and distributing the thrust equally over the two buffers on the curves of the track. 100

Fig. 1 is a side elevation of the car. 105

Fig. 2 is a vertical longitudinal section through the axis of a buffer.

Fig. 3 is a plan view of the car.

Fig. 4 is a horizontal section above one pair of horizontal wheels. 110

Fig. 5 is a horizontal section through one pair of horizontal wheels.

Fig. 6 is a horizontal section through the axis of the buffers.

5 Fig. 7 is a transverse section through the axis of one pair of horizontal wheels.

Fig. 8 is a transverse section through the axis of a beam of the balanced buffers.

Fig. 9 shows, by way of example, the 10 application of the devices of the present invention to a heavy train running on a line having steep inclines and steep descents, and having consequently at front and rear a locomotive and a buffer brake tender.

15 In Figs. 1, 3, 4, 5 and 7 the axles *a* of the horizontal wheels *b* are mounted in the supports *c* sliding between the transverse guides *e* which connect the side frames of the car. The gripping pressure of the 20 wheels *b* against the central rail and the pressure of the brake blocks *f* against these wheels are produced by the spring *g* when it overcomes the reduced pressure in the oppositely acting air cylinder *h* (which is 25 single acting) through the medium of a lever *i* which acts on the one hand, to effect the gripping pressure upon the levers *j* and *k* coupled by the connecting rod *l* and jointed at their lower ends to the supports 30 *c*, and on the other hand to actuate the brake blocks upon the levers *m* and *n* coupled by the connecting rods *o*. The blocks *f* are mounted to slide in the supports *c*.

One of the ends of the spring *g* is fixed 35 against the cylinder *h* attached to the framework of the car, the other end bearing against a shoulder on the piston rod of this cylinder. In the case of a train fitted with continuous air brakes the pipe *p* is connected to the train pipe, so that when the air 40 pressure in the train line is reduced to apply the brakes to the vertical wheels the application of the brake of the horizontal wheels is simultaneous with the application 45 thereof to the vertical wheels.

When the air pressure is at its greatest in the cylinder *h* the spring has no effect on the horizontal wheels, the frictional engagement and the brake power of which 50 are at zero; these wheels pass therefore with a slight clearance against the central rail or run along this rail without gripping it, which is also indispensable when the train descends an incline so that the car 55 suffers no resistance to its movement from the said horizontal wheels.

In proportion however as the air pressure diminishes in the cylinder *h* by the will of the driver, the spring *g* becomes 60 ponderant and augments the pressure of the horizontal wheels against the central rail and that of the brake blocks *f* against these wheels. In cases where the train is fitted with a continuous vacuum brake, the 65 oppositely acting cylinder *h* is a vacuum

cylinder. In the case of an emergency application of the brakes or the rupture of the brake pipe couplings which also interrupts the train pipe, the pressure falls completely in this pipe and the spring *g* produces its maximum effect for the automatic application of the brakes to the horizontal wheels at the same time as it causes them to grip the central rail.

It is well known that the efficacious application of the brakes to the vertical wheels of railway vehicles is obtained by proportioning suitably the pressure of the brake blocks to the frictional engagement of the wheels upon the rails. This condition is 75 fulfilled for the horizontal wheels by the levers *j*, *k*, *m*, *n* of which are of fixed length, by insuring that the gripping pressure of the horizontal wheels against the central rail is adjusted to that, properly speaking, 80 produced by the levers *j* and *k* and the pressure of the blocks *f* transmitted against this rail by these horizontal wheels.

The pivot point of these levers *j* and *k* upon the supports *c* and of the levers *m* and *n* upon the blocks *f* is placed in the horizontal plane of the axis of the central rail 90 so that the axles *a* remain parallel and that no jamming of the supports *c* is produced in their guides *e* when the horizontal wheels *b* move at right angles to the track. When this movement takes place, these wheels therefore have only to overcome 95 very slight friction compared with the forces transmitted by the levers and are easily capable, when inclines are descended, the brakes being applied meanwhile, of following sinuosities of the central rail if its width varies or if it is not mounted regularly in the center of the track, and of following it also over the curves of the track.

In consequence of this easy movement of the horizontal wheels the central rail may be mounted with considerable latitude with relation to the two rails of the track. Great 100 latitude is also permitted with respect to height of this rail seeing that the treads of the horizontal wheels may have all the necessary height.

Figs. 1, 2, 3, 8 show, by way of example, a 115 system of balanced buffers, having at each end of the car buffer bars *q* with nuts *r* adapted to work in the guides *s*, *t*, and two springs *u*, two sleeves *v* carrying journals connected to the ends of the lever *x* by 120 means of slides *y*. The lever *x* rocks about the fixed axle *z* of the support *a'*.

When the car is interposed in a train for the purpose of applying the brakes thereto, on the straight parts of the track the two 125 rods *q* are equally distant from the frame, the lever *x* is at right angles to the longitudinal axis of this frame and the two springs are equally stressed. When the car passes around a curve, the rod *q* located 130

nearest the center of the curve passes into the frame and the other rod emerges therefrom; the lever α assumes an oblique position with relation to the axis of the frame, but the two springs u are equally stressed. The thrust is equally distributed over the two buffers whatever its amount may be and whatever the radius of the curve of the track may be.

10 This therefore avoids the application to a single buffer of the powerful thrust produced on steep slopes, which application would abnormally strain this buffer and also the whole of the frame and would 15 cause the stock to be jammed by the vertical wheels against the two rails of the track which might cause derailment. The system of balanced lateral buffers is applicable to 20 locomotives in which a supplemental gripping action is obtained by means of horizontal wheels and a central rail.

When the track has steep declivities in one direction only, one or more buffer brake cars may be advantageously placed at the 25 lowest part of the train; other brake cars being interposed along the length of the train if the brake power to be produced is very great.

When the track has steep declivities in 30 both directions that is to say ascents and descents, one or more brake cars are placed at each end of the train.

In Fig. 9 the train b' , which is hauled by two locomotives c' equipped with horizontal 35 wheels for engagement with a central rail, has two buffer brake cars d' used as tenders of these locomotives. Like these tenders, the said locomotives are provided with balanced lateral buffers.

40 Each of these tenders is represented as having three pairs of horizontal wheels e' and has the body f' loaded with water and coal.

In the case where the stock hauled is not 45 provided with a continuous air or vacuum brake so that the locomotives and the tenders and also the brake cars, if such be interposed in the train, apply the brakes simultaneously when the driver opens his 50 brake valve or when a rupture of the brake couplings takes place, a removable train pipe g' is placed upon the stock without modifying it. This pipe is formed of flexible or rigid components of easily manipulatable length having a coupling at each 55 end. These components are carried by the tenders or the brake cars when they are not in use.

If it be desired to employ the brake car 60 without a locomotive to haul trains down steep inclines, it suffices to provide the car with an air reservoir intended to supply the cylinders h (see Fig. 7) and the train pipe of this car. In this case the brakes are applied by a man who is placed upon the said

car and works a brake valve placed on the train pipe.

What I claim and desire to secure by Letters Patent of the United States is:—

1. An improved brake car having vertical 70 wheels adapted to engage the usual track rails; pairs of horizontal wheels disposed at opposite sides of a supplemental rail located intermediate the track rails, the pairs of horizontal wheels being adapted to grip 75 the opposite sides of the supplemental rail when brought into contact therewith; brakes for the horizontal wheels and mechanism for effecting automatically and simultaneously the engagement of the horizontal 80 wheels with said supplemental rail and the braking of said wheels.

2. An improved brake car having vertical wheels adapted to engage the usual track 85 rails; pairs of horizontal wheels disposed at opposite sides of a supplemental rail located intermediate the track rails, the pairs of horizontal wheels being adapted to grip the opposite sides of the supplemental rail when brought into contact therewith; 90 brakes for the horizontal wheels and mechanism for effecting automatically and simultaneously the engagement of the horizontal wheels with said supplemental rail and the braking of said wheels; said mechanism being operated by a spring which is controlled by an oppositely-acting piston controlled by the difference in fluid pressure exerted 95 against its two faces.

3. An improved brake car having vertical 100 wheels adapted to engage the usual track rails; pairs of horizontal wheels disposed at opposite sides of a supplemental rail located intermediate the track rails, the pairs of horizontal wheels being adapted to grip the 105 opposite sides of the supplemental rail when brought into contact therewith; brakes for the horizontal wheels and mechanism for effecting automatically and simultaneously the engagement of the horizontal 110 wheels with said supplemental rail and braking of said wheels; said mechanism being operated by a spring which is controlled by an oppositely-acting compressed-air cylinder.

4. An improved brake car having vertical 115 wheels adapted to engage the usual track rails; pairs of horizontal wheels disposed at opposite sides of a supplemental rail located intermediate the track rails, the pairs of horizontal wheels being adapted to grip the 120 opposite sides of the supplemental rail when brought into contact therewith; brakes for the horizontal wheels and mechanism for effecting automatically and simultaneously the engagement of the horizontal 125 wheels with said supplemental rail and the braking of said wheels; said mechanism being operated by a spring which is controlled by an oppositely-acting piston controlled by the difference in fluid pressure exerted against 130

two faces and working in a cylinder which is connected with the main air pipe of the train.

5. An improved brake car having vertical 5 wheels adapted to engage the usual track rails; pairs of horizontal wheels disposed at opposite sides of a supplemental rail located intermediate the track rails, the pairs of horizontal wheels being adapted to grip 10 the opposite sides of the supplemental rail when brought into contact therewith; brakes for the horizontal wheels and mechanism for effecting automatically and simultaneously the engagement of the horizontal 15 wheels with said supplemental rail and the braking of said wheels; said mechanism being operated by a spring which is controlled by an oppositely-acting, compressed-air cylinder which is connected to a detachable 20 compressed-air pipe carried by the train.

6. An improved brake car having vertical 65 wheels adapted to engage the usual track rails; pairs of horizontal wheels disposed at opposite sides of a supplemental rail located 25 intermediate the track rails, the pairs of horizontal wheels being adapted to grip the opposite sides of the supplemental rail when brought into contact therewith; brakes for the horizontal wheels and mechanism for 30 effecting automatically and simultaneously the engagement of the horizontal wheels with said supplemental rail and the braking of said wheels; the said mechanism being so arranged and the mounting of the 35 horizontal wheels being such that the gripping action of said wheels and their braking are independent of wear upon the various parts of said mechanism and upon the supplemental rail.

40 7. An improved brake car having vertical wheels adapted to engage the usual track rails; pairs of horizontal wheels disposed at opposite sides of a supplemental rail located intermediate the track rails, the pairs of

horizontal wheels being adapted to grip the 45 opposite sides of the supplemental rail when brought into contact therewith; brakes for the horizontal wheels and mechanism for effecting automatically and simultaneously the engagement of the horizontal 50 wheels with said supplemental rail and the braking of said wheels; the said mechanism being so arranged and the mounting of the horizontal wheels being such that the said wheels can move freely one with relation to the other, or both in the same direction, transversely of the track in order to permit them to adapt themselves to variations in the width of the supplemental rail and its irregularities in position with relation to 60 the track rails, as well as to permit them to follow the curves of the track.

8. In a train of cars, a plurality of variably-disposed brake cars, each provided with vertical wheels adapted to engage the usual 65 track rails and with pairs of horizontal wheels disposed at opposite sides of a supplemental rail located intermediate of the track rails, the pairs of horizontal rails being adapted to grip the opposite sides of 70 the supplemental rail when brought into contact therewith; brakes for the horizontal wheels and mechanism for effecting automatically and simultaneously the engagement of the horizontal wheels with said supplemental rail and the braking of said 75 wheels; said mechanism being operated by a spring which is controlled by an oppositely-acting, compressed air cylinder, which is connected to a detachable compressed air 80 pipe carried by the train.

In testimony whereof I have signed this specification in the presence of two subscribing witnesses.

JULES ETIENNE HANSOTTE.
